By his Attorneys,

Inventor
Philip Hise,

C. A. Brown & Co.

UNITED STATES PATENT OFFICE.

PHILIP HISE, OF CINCINNATI, OHIO.

DOOR-SECURER.

SPECIFICATION forming part of Letters Patent No. 445,273, dated January 27, 1891.

Application filed April 26, 1890. Serial No. 349,644. (No model.)

To all whom it may concern:

Be it known that I, PHILIP HISE, a citizen of the United States, residing at Cincinnati, in the county of Hamilton and State of Ohio, 5 have invented a new and useful Door-Securer, of which the following is a specification.

The invention relates to improvements in door-securers.

The object of the present invention is to 10 provide a simple, inexpensive, and efficient door-securer adapted to be conveniently carried and capable of being readily adjusted to a door without injuring or defacing the casing.

15 The invention consists in the construction and novel combination and arrangement of parts hereinafter fully described, illustrated in the accompanying drawings, and pointed out in the claim hereto appended.

20 In the drawings, Figure 1 is a perspective view of a door-securer constructed in accordance with this invention and shown applied in operative position to a door. Fig. 2 is a longitudinal sectional view of the same. Fig. 25 3 is a transverse sectional view. Figs. 4, 5, and 6 are detail views of the parts separated.

Referring to the accompanying drawings, 1 designates a door-securer, constructed of suitable metal and composed of sections 2 30 and 3, adapted to engage a door and its casing, and having their opposed faces 4 and 5 provided with teeth or corrugations reversely shouldered and adapted to engage each other to prevent the sections when fitted together 35 slipping longitudinally along each other. Each section has one end 6 bent laterally and adapted to engage the door 7 or casing 8, and the end 6 of the section 2 is fitted in the recess of the lock-plate of the casing 8, and the 40 door is then closed to secure the section 2, and the other section has its laterally-bent end 6 arranged opposite and projecting from the end of the section 2, and the said laterally-bent end of the section 2 is fitted against 45 the door, and the corrugated or shouldered faces of the sections are brought together to

prevent the sections slipping and to secure the door. The section 2 is provided with a longitudinal slot 9, extending inward from the end 10, and the other section is provided 50 with a block 11, secured centrally to and longitudinally along the shouldered face of the section 3, and provided with side faces 12, that incline inward and converge toward the section, and in order to secure the block in 55 the longitudinal slot 9 to hold the teeth 4 and 5 into engagement with each other and prevent the sections slipping a key-plate 13 is employed. The key-plate 13 is provided with a longitudinal slot 14, having beveled side walls 60 adapted to engage the inwardly-inclined faces 12 of the block to press the teeth into engagement with each other, and the said plate 13 is provided at one end with a vertical flange 15, which serves as a handle and enables the 65 key-plate to be readily brought into and removed from engagement with the block 11.

It will readily be seen that the door-securer is simple, effective, and inexpensive in construction and adapted to be readily applied 70 and quickly adjusted to any door, and is capable of securely holding the same.

What I claim is—

In a door-securer, the combination of the sections 2 and 3, provided with laterally-bent 75 ends 6 and having their opposed faces provided with teeth oppositely shouldered, the section 2 having the longitudinal slot 9, the block 11, secured to the section 3 and provided with inwardly-inclined sides 12 and 80 8c adapted to be arranged in the slot 9, and the key-plate provided with the slot 14 and having the beveled edges and adapted to engage the block, substantially as described.

In testimony that I claim the foregoing as 85 my own I have hereto affixed my signature in presence of two witnesses.

PHILIP HISE.
